UNITED STATES PATENT OFFICE

CLIFTON H. ANGELL, OF WESTFIELD, MASSACHUSETTS

PRICE TAG AND SIGN

Application filed April 28, 1930. Serial No. 447,795.

This invention relates to improvements in price tags and signs.

An object of the invention is to provide an interchangeable combination of holder, identification cards and price figures, in such a manner that the whole sign or tag, or any part thereof, may be easily attached to the article to be displayed.

The present invention, broadly considered, 10 comprises a holding or supporting device with means for attaching the same to the article displayed, and also means for holding various inserts or descriptive matter to be inserted in the holder for the purpose of informing the public of the nature and price of the article, upon or near which this invention is placed.

The holder, of metal or similar material, is composed of a flat mat with an extended 20 flange or band on each of its four sides. The flanges or bands at top and bottom are bent forward to form channels or guides for inserted signs or numerals and the flanges or bands at the sides are bent backward to form 25 channels or guides for inserted signs on the back of the holder. Attached to the back of the holder is a staple, clip, or other means of attaching the holder to an article to be displayed.

30 As a modification, means is provided for removably attaching the price tag to the edge of a shelf, or the like.

Referring to the drawings:

Fig. 1 is a front or elevational view of the 35 assembled sign or tag.

Fig. 2 is a rear or elevational view of the assembled sign or tag.

Fig. 3 is a sectional view on the line 3—3 of Fig. 1 showing the turned-over edges at 40 the front side.

Fig. 4 is a sectional view on the line 4—4 of Fig. 1 showing the turned-over edges or channels at the rear.

Fig. 5 is a view of typical removable numerals used for pricing, and

Fig. 6 is a perspective view showing alternate means of attachment of sign or tag to a shelf or article by means of a clip, instead of prongs.

50 Referring to the drawings in detail:—

1 indicates a mat of suitable material, such as aluminum or its alloys, or other metal, which is formed with the turned or folded flanges or guides 2 and 3 at its top and bottom edges and 4 and 5 at its side edges. These 55 flanges are so turned as to leave spaces or channels 6 and 7 for the insertion of cards 8 and 9, and, numerals or other indicators 10 and 11, two of which are shown removed in Fig. 5. These numerals are preferably 60 formed from celluloid.

Secured to the back of the mat 1 is a staple-shaped piece 12, attached thereto by means of raised, or struck-up portions 13 and 14, of the mat 1. As a further means of support, 65 the raised portions 15 and 16 of the mat 1, engage in the loops 17 of the staple 12. The ends 18 and 19 of the staple 12 are pointed or sharpened for the purpose of inserting them 70 into an article to be displayed. The top or horizontal member 20 of the staple 12 acts as a stop or support for the card 9, which is inserted in the channels 7 at the top and pushed downward until stopped by 20.

Suitable printing or lettering, 21 and 22, 75 may be displayed on the cards 8 and 9, as may be necessary to convey the desired information.

After the card 8 is inserted in the channels 6, numerals or letters, such as 10 and 11, are 80 inserted above the card 8. These numerals, 10 and 11 are made separate and interchangeable, of celluloid or cardboard, or similar material, and colored, or not, to suit convenience. At top and bottom of numerals 10 and 11 85 are projections 23, 24, 25 and 26 to serve as spacing guides and for the support of the numerals in the channels 6 of the mat 1. At the ends of these projections, 23, 24, 25 and 26 are other smaller projections 27, which 90 act as spacers for the letters or numerals.

Referring to Fig. 6, 28 represents a clip riveted or fastened to the mat 1 for the purpose of attaching same to a shelf or projecting edge of some sort, 29, showing adaptability of invention by substitution of various simple means of fastening.

From this description, it will be seen I have provided an improvement in tags or price signs for increasing their adaptability, 100

usefulness and length of service; also, one that is inexpensive to construct.

What I claim is:

1. The combination in a price tag, of a base piece formed with channels on its opposite faces, the channels on the rear face being designed to receive a card indicating the name of the article, means for retaining the card with a portion above the upper edge of the base piece, and staple means for attaching the tag to an article.
2. The combination in a price tag, of a base piece formed with channels on its opposite faces, the channels on the rear face being designed to receive a card indicating the name of the article, means for retaining the card with a portion above the upper edge of the base piece, staple means for attaching the tag to an article, and numerals located in the channels on its front face indicating the price, the numerals having their opposite ends formed with spacing extensions.
3. A price tag comprising a base member formed with top and bottom edges folded forward to form channels, and side edges folded backward to form channels, a card indicating the name of the article located in the channels folded backward, price figures having their ends in the channels folded forward, and means for attaching the tag to a support.
4. A price tag comprising a base member formed with adjacent edges folded alternately to form channels on the front and rear faces of said base member, a card for indicating the name of the article removably retained in the channels on the rear face of said base member, a blank card removably retained in the channels on the front face of said base member, separate price figures of celluloid or the like having their ends also in the channels on the front face of said base member, said figures being superimposed on the face of said blank card, and means for attaching said base member to a support, said means comprising a staple secured to the back of the base member.
5. A price tag comprising a mat member having its adjacent edges folded in opposite directions to form channels, cards removably located in the channels on the front and rear faces of the mat member, price numerals in the channels on the face of the mat member, a staple attached to the back of the mat member, the staple serving to retain the card on the rear face of the mat member against downward movement.

CLIFTON H. ANGELI.
